WILLIAM A. PARIS, OF EDGEWOOD PARK, PENNSYLVANIA, ASSIGNOR TO WESTINGHOUSE ELECTRIC & MANUFACTURING COMPANY, A CORPORATION OF PENNSYLVANIA.

ELECTRIC SWITCH.

1,015,972.

Specification of Letters Patent.

Patented Jan. 30, 1912.

Application filed September 25, 1905. Serial No. 279,980.

To all whom it may concern:

Be it known that I, WILLIAM A. PARIS, a citizen of the United States, and a resident of Edgewood Park, in the county of Allegheny and State of Pennsylvania, have invented a new and useful Improvement in Electric Switches, of which the following is a specification.

My invention relates to switches for electrical circuits, and particularly to switches that are electro-magnetically operated and are provided with blow-out windings.

The object of my invention is to provide a simple and improved structure and arrangement of the parts of switches of the character designated whereby the magnetic circuit of the blow-out winding may be at least partially coincident with that of the operating electro-magnet.

Figure 1 of the accompanying drawing is a view, partially in side elevation and partially in section, of a switch constructed in accordance with my invention, and Fig. 2 is a view, mainly in front elevation but partially in section, of the switch shown in Fig. 1.

Mounted upon a slab or base 1 of marble, or other suitable insulating material, and fastened thereto by means of bolts 2 and lugs 3, is a magnetizable member 4 that comprises a substantially rectangular frame 5 which surrounds a solenoid 6 and constitutes the greater portion of the magnetic circuit thereof, a core portion 5^a that projects into the upper end of the solenoid 6, and upwardly extending portions 7 the free ends of which are provided with inwardly extending cylindrical bosses 8 having opposing faces.

The solenoid 6 is provided with a movable core 9 to which is attached the lower end of a rod 10 that projects through an opening in the portion 5^a of the magnetizable frame and is threaded, at its upper end, to a contact terminal piece 11, a lock-nut 12 being provided to prevent alterations in the adjustment of the connection. The contact terminal piece 11 is located between the opposing faces of the frame extensions 7 and comprises stepped surfaces 13 and 14 with which the respective stationary spring-supported contact terminals 15 and 16 are

adapted to engage. A detachable plate 17 may be utilized to provide the contact surface 14 in order to facilitate repairs made necessary by wear or the mutilation of the terminals by arcs. The terminal piece 11 may be connected to a binding post 18, by means of flexible conductors 19 that pass through an opening 20 in the insulating slab 1, the binding post being secured upon the rear of the insulating slab by means of one of the bolts 2 which passes through the insulating slab and is threaded into one of the lugs 3.

The contact terminals 15 and 16 may be secured, by means of springs 21 and 22, to a suitable block 23 that is secured upon the front of the insulating slab by means of a bolt 24 which projects through the insulating slab and the outer end of which may be provided with an extra nut 25 to serve as a binding post or clamping means for connecting to an external circuit.

The frame extensions 7 constitute pole pieces for the blow-out winding that comprises two coils 26 and 27 which are mounted upon the respective projections 8, the coils being connected together by means of terminal leads 26^a and 27^a and in series in the circuit which the switch is adapted to control, as is usual with such switches. Insulating plates 28 are located between the faces of the polar extension bosses 8 at the outer sides of the separable switch terminals 11, 15 and 16 and are secured in position by means of an angle piece 29 that is fastened to the frame 5 by a bolt 29^a and a bolt 30 that clamps the plates to the outer sides of ears 30^a with which the angle piece is provided.

The switch structure which I have provided is well adapted for the operation of interlocking switches which are frequently employed in connection with circuit-controlling switches for governing the operation of translating devices such as motors. As here shown, an insulating disk 31 is fastened to the lower end of the movable armature core 9 by means of a bolt 32 and conducting strips 33 and 34 are secured to the faces of the disk so as to be engaged by suitable contact fingers 35 and 36 that are suitably mounted upon the front of the insulat-

ing slab 1. I have also provided my switch with an auxiliary switch that comprises a movable terminal piece 37 formed on or attached to the head of the bolt 32 and operated to engage a suitable stationary terminal piece 38 that is supported upon the free end of a bracket 39, which projects from the slab 1.

The movable armature core 9 is prevented 10 from rotation by means of a set-screw 40 that is screwed into the frame 5 and the inner end of which is located in a suitable groove 41 with which the core is provided.

It will be observed that the upper, horizontal portion of the frame 5 serves as a portion 15 of the magnetic circuit for the operating solenoid 6 and also as a portion of the magnetic circuit for the blow-out winding; that is, the two magnetic circuits are partially coincident. The structure and arrangement of the parts of the switch are otherwise such as provide a simple and compact device, and it is to be understood that 20 any of the details of construction and arrangement may be modified somewhat from what is herein shown and described without departing from the scope of the invention.

I claim as my invention:

1. The combination with two spring-supported contact terminals, a movable core 30 having a contact member to engage said terminals successively, a solenoid surrounding said core, and a magnetizable solenoid frame having extensions provided with pole pieces in proximity to said contact terminals, and blow-out coils surrounding said pole pieces.

2. The combination with two contact terminals, a movable core having a contact 40 member provided with contact faces that make successive yielding engagement with said contact terminals, a solenoid surrounding said core, and a magnetizable solenoid frame having integral projections provided 45 with pole pieces the faces of which are located adjacent to and on opposite sides of the contact terminals, of blow-out coils surrounding said pole pieces.

3. The combination with two contact terminals, a movable core having a contact 50 member to engage said terminals, a solenoid surrounding said core, and a magnetizable solenoid frame having extensions provided with inwardly-projecting pole pieces the 55 faces of which are adjacent to said contact terminals, of blow-out coils surrounding said pole pieces.

4. The combination with two contact terminals the contact faces of which are offset 60 from each other both laterally and longitudinally, and a longitudinally movable core having a contact member to make successive engagement with said contact terminals, of a solenoid surrounding said core, a magnetizable solenoid frame having integral exten- 65

sions provided with laterally-projecting pole pieces adjacent to the contact terminals, and blow-out coils surrounding said pole pieces.

5. The combination with two electrically connected but separately yielding contact terminals, a longitudinal core having a contact member provided with faces adapted to successively engage said contact terminals, and a solenoid surrounding said core, of a magnetizable solenoid frame having extensions 70 provided with pole pieces adjacent to said contact terminals, and blow-out coils to energize said pole pieces.

6. The combination with a base and two electrically connected but independently 80 yielding contact terminals supported thereby, of a solenoid having a core provided with a contact member to engage said contact terminals successively, a magnetizable solenoid frame having integral extensions 85 terminating in pole pieces adjacent to said contact terminals, and blow-out coils for said pole pieces.

7. The combination with a base, two electrically connected spring arms of different 90 lengths which project laterally from said base, and contact pieces attached to the ends of said arms, of a movable contact member flexibly connected to a terminal on said base and having stepped or offset contact surfaces, means for actuating said member parallel to said base to make successive engagement with said contact pieces, and a blow-out winding the magnetic circuit of which passes through said contact member and 10 pieces.

8. The combination with a base, two electrically connected spring arms of different lengths which project laterally from said base, and contact pieces attached to the ends of said arms, of a longitudinally movable contact member flexibly connected to a terminal on said base and having stepped or offset contact surfaces, means for actuating said member to make successive yielding engagement with said contact pieces, and a blow-out winding the magnetic circuit of which passes through said contact member and pieces.

9. The combination with a base, of two 11 electrically connected spring arms of different lengths which project laterally from said base, contact pieces attached to the ends of said arms, a solenoid, a core therefor, and a contact member mounted upon said core and 12 having stepped or offset contact surfaces for movement parallel to said base and into successive engagement with said contact pieces.

10. The combination with a base provided 12 with circuit terminals, of two laterally projecting spring arms supported by said base and electrically connected to one of the circuit terminals, contact pieces attached to the ends of said spring arms, a coöperating con- 13

tact member flexibly connected to another of said circuit terminals and having stepped or offset contact surfaces, and means for actuating said member parallel to said base to make successive yielding engagement with said contact pieces.

In testimony whereof, I have hereunto

subscribed my name this 22nd day of September, 1905.

WILLIAM A. PARIS.
